UNITED STATES PATENT OFFICE.

PAUL C. RICHTER, OF STAMFORD, CONNECTICUT, ASSIGNOR TO THE YALE & TOWNE MANUFACTURING COMPANY, OF STAMFORD, CONNECTICUT.

DOOR-CLOSER.

1,315,156.

Specification of Letters Patent.

Patented Sept. 2, 1919.

Application filed February 3, 1919. Serial No. 274,765.

To all whom it may concern:

Be it known that I, PAUL C. RICHTER, a citizen of the United States, and a resident of Stamford, in the county of Fairfield 5 and State of Connecticut, have invented certain new and useful Improvements in Door-Closers; and I do hereby declare the following to be a full, clear, and exact description of the invention, such as will enable others 10 skilled in the art to which it appertains to make and use the same.

My invention relates to improvements in that type of door closers having means for normally holding a door in open position, 15 and it consists in improved means for releasing the door holding means in the event of a fire, so that the door will then automatically close and thus cut off the draft and assist in confining the fire to the room 20 in which it started.

In the accompanying drawings; Figure 1 is a plan view of a portion of a door closer with my improvement applied thereto; Fig. 2 is a view in side elevation, partly 25 in section of the same; Fig. 3 is a plan view of the two part seat; Fig. 4 is a view in section of the lever arm, on the line $\alpha\alpha$ of Fig. 1, and Figs. 5, 6 and 7 are views similar to Figs. 1, 2 and 4, of a modified 30 construction.

The improvement is designed for use with door closers, or with combined checks and closers, consequently I do not confine its application to either, and in the use of the 35 term door closer, I intend to include combined checks and closers.

10 represents the casing of a door closer, and 11 is the spindle to which the lever arm 12 is secured, the said lever arm being adapt- 40 ed for coöperation with the mechanism of the door closer and with the door in the usual and well known manner.

For the purpose of holding the door open, the lever arm 12 is provided with a spring 45 pressed dog 13, and the cap of the closer casing is provided with an upwardly projecting stop or rib 14 which is engaged by the lower beveled end of the dog when the door is in its open position, the dog riding 50 over the stop during the opening movement of the door and dropping behind the same when fully open, the pressure of the spring bearing against the dog being sufficient un-

der normal conditions to prevent the latter from rising out of engagement with the stop, 55 but not of course preventing the free manual operation of the door to either close or open the same. The dog 13 is mounted to move vertically in the lever arm 12 and is provided with a chisel or beveled lower end to 60 engage the stop 14, and with a head which limits its downward movement and against which the free end of the long flat spring 15 bears, the head of the dog being grooved to receive the end of the spring, whereby 65 the latter prevents the dog from turning in its bearing.

The opposite end of spring 15 is supported by the pin 16 which is preferably shouldered as at 17 to form a seat for the 70 spring. The spring 15 may be secured to the pin 16 or it may be loosely seated on the same, the function of the pin being to hold the spring in its normal position and under tension so long as it remains properly seated, 75 as hereinafter explained. This pin is loosely mounted in an opening through the lever arm 12 and projects below the latter and is made conical at its lower end as shown in Fig. 2. Suspended from the lever arm 12 80 is the saddle 18 the side arms of which rest on the upper face of the lever arm and are preferably curved to conform to the contour of the latter. The lower member of this saddle is provided with an opening 18^a 85 through the same, the said opening being of slightly greater diameter than the pin 16, and located in the vertical plane of the latter so that when the pin support carried by the saddle separates, the pin will be free to 90 fall into or through the hole 18^a and thus release the end of the spring 15, which is normally supported by the said pin.

The pin support 19 consists of two members made of comparatively thin metal and 95 each preferably composed of two disk shaped ends connected by a narrow neck, each of the latter being cut away approximately at its center so that when the two parts of the seat are assembled the cut away portions of 100 the necks thereof form a circular open seat in which the conical end of the pin 16 rests. The two disk shaped ends of one part of the support are placed on the ends of the other part and the two parts are secured together 105 by a readily fusible alloy or solder between

the disk shaped ends, and when so assembled the necks of the two members rest side by side and form the seat for the pin.

The tension of the spring 15 is created and regulated by the tension bolt 20, which passes loosely through a hole in the lever arm and through a hole in the spring and carries a nut 21 at its outer end. By adjusting the nut up or down on the bolt the tension of the spring will be decreased or increased. It is evident however that instead of using a nut the hole in the spring may be threaded to engage the threads on the bolt.

With this construction it will be seen that when the spring 15 is put under tension by the tension bolt 20, which is located intermediate the ends of the spring, it will bear at one end on the dog 13 and at the other end on the pin 16, and the conical end of the pin resting within the two part seat on the pin support, tends to spread or separate the latter, and thus permit the pin 16 to drop. The ends of the pin support 19 are removed from the lever arm 12 and also removed from the saddle, and are therefore directly exposed to the influence of any heat, hence if the temperature rises abnormally and to a degree sufficient to fuse the alloy or solder, the latter quickly melts and releases the two parts of the seat 19 so that the pressure of the spring 15, transmitted through the conical end of the pin, instantly separates the seat sections and thus removes the support for the pin. The removal of the pin support or seat, relieves the spring of its tension thus leaving the dog 13 free to rise over the stop 14 under the closing action of the spring in the closer.

In the construction shown in Figs. 5, 6 and 7, I have dispensed with the saddle 18 and seated the pin 16^a on the top of the lever arm 12, the shoulder 16^b on the pin resting on the top of the lever arm and preventing any downward movement of the pin. The top surface of the pin is in the shape of an inverted cone on which the seat 19^a rests, the latter being constructed precisely like the seat 19 except that its ends are bent downwardly as shown in Fig. 7.

The spring 15^a is provided at its end over the pin 16^a with a hole of greater diameter than the pin, so that when the seat 19^a is destroyed by the melting of the alloy or solder securing the two parts thereof together, the end of the spring can drop onto the upper face of the lever arm and thus remove the tension of the spring on the dog 13. In this latter form I have shown the tension bolt 20 engaging a threaded opening in the screw thus dispensing with the nut shown in Fig. 2.

It will of course be understood that with a construction wherein the tension of the spring is removed by the removal of the seat for the outer end of the spring, the tension

bolt should have a loose fit in the lever arm, or the spring a loose fit on the tension bolt so that when the end seat of the spring is removed the spring will not bind on the tension bolt or the latter not bind in the lever 70 arm, but that one of said parts will be free to move, so as to relieve the tension on the dog 13.

It is evident that many slight changes might be resorted to in the relative arrangement of parts shown and described without departing from the spirit and scope of my invention. Hence I would have it understood that I do not wish to confine myself to the exact construction and arrangement 80 shown and described but,

Having fully described my invention what I claim as new and desire to secure by Letters Patent, is:

1. The combination of a door closer having a stop, a lever arm, a dog mounted in said lever arm and engaging the stop for holding the door open, a spring one end of which bears on said dog, a collapsible seat for the other end of said spring, the said seat being carried by the lever arm and secured in fixed position on the latter by fusible solder, and a tension bolt carried by the lever arm and engaging the spring intermediate its ends for adjusting the tension 95 of the spring.

2. The combination of a door closer having a stop, a lever arm, a dog mounted in said lever arm and engaging the stop for holding the door open, a spring one end of which bears on said dog, a tension bolt for the spring, a pin carried by the lever arm and having a tapering surface and a two part seat coacting with the tapering surface of the pin for supporting the other end of said spring, the two parts of said seat being held together by a fusible alloy which when it melts permits the parts of the seat to spread under the influence of the tapering surface and thus release the end of the 110 spring supported by the same.

3. The combination of a door closer having a stop, a lever arm, a dog mounted in the lever arm and engaging the stop for holding the door open, a spring one end of which bears on the said dog, a two part seat supported on and carried by the lever arm and supporting the other end of the spring, the parts of said seat being connected together by a fusible material and adapted to separate when said material melts and thus destroy the support for the spring and a tension bolt carried by the lever arm and engaging the spring intermediate its ends.

4. The combination of a door closer having a stop, a lever arm, a dog mounted in the lever arm and engaging the stop for holding the door open, a spring, one end of which bears on said dog, a tension bolt for the spring, a saddle carried by the lever 130

arm, a two part seat carried by the saddle the parts of said seat being connected by fusible solder and a pin passing through the lever arm and having a conical end resting on a bearing formed in the two parts of the seat, the said pin forming a support for the outer end of the spring.

In testimony whereof I have signed this specification in the presence of two subscribing witnesses.

PAUL C. RICHTER.
